UNITED STATES PATENT OFFICE.

LESLIE B. HOYT, OF ATHENS, MAINE, AND ERNEST E. CURRIER, OF WHITEFIELD, NEW HAMPSHIRE.

HARNESS-TERRET.

1,129,804.

Specification of Letters Patent. Patented Feb. 23, 1915.

Application filed February 27, 1914. Serial No. 821,419.

To all whom it may concern:

Be it known that we, LESLIE B. HOYT and ERNEST E. CURRIER, of Athens, in the county of Somerset and State, of Maine, and Whitefield, county of Coos, State of New Hampshire, respectively, have invented certain new and useful Improvements in Harness-Terrets, of which the following is a specification.

10 Our invention relates to a harness terret of that class which is constructed with a lateral opening to enable the rein to be inserted from the side or top and without threading through the terret.

15 The object of our invention is to utilize such a terret as a means of using the regular reins for preventing the horse from lowering his head to feed from the ground and also to prevent him from turning his head 20 sidewise more than a limited amount. We accomplish this object by securing to the reins in rear of the terret a clamp which is larger than the opening through the terret.

Our invention may best be illustrated 25 by means of the accompanying drawing, in which is shown a harness saddle provided with our terrets together with the rein provided with the clamp.

30 In the drawing, Figure 1 is a side elevation of a harness saddle showing one of our terrets in position, Fig. 2 is a front elevation of the individual terret, Fig. 3 is a plan of the terret, and Fig. 4 is an elevation of the clamp showing the rein in section.

35 Referring to the drawing, A represents the saddle, B is one of our turrets, C is one of the reins and D is the bit.

40 The terret is generally circular in form and is made with a main opening b which is preferably a little larger than the rein so that the latter is a fairly close fit. The main opening b extends with parallel upper and lower edges from side to side of the terret. The upper portion of the terret is

cut away to form a lateral opening b' connecting with the main opening and through the opening b' the rein may be inserted without being threaded through the main opening of the terret. The opening b' as here shown connects with one end of the 50 main opening and it extends upwardly and in a curved line to the top of the terret. From front to rear the opening makes an angle with the face of a terret so there is no danger of the rein accidentally being 55 thrown out of the terret.

In rear of the terret we secure to the rein a clamp E which is larger than the main opening in the terret so that it constitutes a stop which prevents the rein from being 60 drawn through the terret, except for a limited distance. The clamp is formed of two halves, with a recess between them fitting over the rein and a screw for holding the two halves together. The clamp thus acts 65 to convert the ordinary rein into a check rein for certain purposes that is, it prevents the horse from lowering his head far enough to feed from the ground. The terret may be used with or without the clamp 70 being much more convenient than the ordinary terret in which it is necessary to thread the rein through from front to rear.

We claim;—

A harness terret having a horizontally 75 elongated main opening and a restricted auxiliary opening extending from the said main opening obliquely upward to the top of the terret and making an angle with the faces of the terret for releasing the rein 80 laterally.

In testimony whereof we have affixed our signatures, in presence of two witnesses.

LESLIE B. HOYT.
ERNEST E. CURRIER.
